(57) CLAIM

The ornamental design for an overcap for dispensing closure, as shown and described.

DESCRIPTION

FIG. 1 is a perspective view of an overcap for dispensing closure showing our new design;

FIG. 2 is a top plan view thereof;

FIG. 3 is a front elevation view thereof, the rear elevation being the same; and,

FIG. 4 is a right side elevation view thereof, the left side elevation being the same.

The bottom and interior of the overcap for dispensing closure forms no part of the claimed design.
